UNITED STATES PATENT OFFICE.

SAMUEL FRIEDMAN, OF BROOKLYN, NEW YORK.

FLESHING MACHINE.

Application filed October 27, 1921. Serial No. 510,723.

To all whom it may concern:

Be it known that I, SAMUEL FRIEDMAN, a citizen of the United States, and a resident of the city of New York, borough of Brooklyn, county of Kings, and State of New York, have invented a new and Improved Flesching Machine, of which the following is a description.

My invention relates to a machine for cutting the flesh from skins and more particularly the invention relates to that type of machine in which the revolving flesching knife has the general form of a disk. In the usual form of the machines referred to the disk is made with a cutting edge integral therewith. In the disk being bent to form the cutting edge, obviously, the metal must be comparatively soft to permit of the bending and therefore the cutting edge does not have the proper hardness and temper for the work and to withstand wear.

The general object of my invention is to provide a knife having an improved cutting edge produced in a manner to permit of the employment of high-grade steel in the manufacture thereof, preferably of piano wire.

A further object of the invention is to provide a knife for the indicated purpose in which the edge portion may be removed and discarded more economically than the grinding thereof can be effected.

More specifically, the invention has in view to provide a knife that initially may be effectively ground with facility and of a form that will enable the cutting edge to be preserved by the whetstone until the edge is substantially worn away.

The nature of the invention and its distinctive features and advantages will clearly appear as the description proceeds.

Reference is to be had to the accompanying drawings forming a part of this specification, it being understood that the drawings are merely illustrative of one example of the invention.

Figure 1 is a side elevation of a flesching machine embodying my invention;

Figure 2 is an elevation at right angles to Figure 1;

Figure 3 is a horizontal section on the line 3—3, Figure 2;

Figure 4 is a partial section on the line 4—4, Figure 2;

Figure 5 is an enlarged transverse section of the knife at the edge;

Figure 6 is a face view of the knife;

Figure 7 is an elevation of the peripheral cutting element;

Figure 8 is an edge view of said element.

In carrying out my invention in accordance with the illustrated example the standard 11 has a suitable base 10 and at the upper end is in the form of an arched integral frame 11^a. The knife of the machines of the type to which my invention relates is usually driven by an electric motor 12 mounted on the standard 11 and driving a belt 13 running upwardly over the hub 14 of a revolving knife, here designated generally by the numeral 15. The knife turns on a shaft 16 supported in any suitable manner in the frame 11^a the shaft securing means including centering screws 17 engaging the ends of the shaft. A guard 18 houses the knife at the side at which the operator stands and at the opposite side separate guards 19 and 20 are disposed at the rear and front of the knife 15, the knife being exposed for a short section at the bottom of the guards 19, 20. The guards 19, 20 are adjustably secured by bolts 22, passing through the slots 22^a of said guard, additional set screws 21 being employed to adjust the guards 19, 20 and hold the same in adjusted position.

The guard 18 is suitably fastened at the top and bottom as at 18^a, 18^b to the frame 11^a and standard 11.

My improved knife 15 is formed in practice of cast metal and generally of dished form. In the grooved outer edge of the disk I employ an edge element 23 of ring form extending continuously about the disk and detachably held in position in a concave peripheral groove 15^a of the disk, said element in practice being formed of piano wire. At the back of the groove 15^a the material of the body extends radially outward a greater distance than at the front of the groove, the lesser radius at the front of the groove facilitating the removal of the annular element 23. The metal at the rear side of the groove 15^a takes the pressure when the knife is in use, the pressure being rearwardly. The ring element 23 is formed with a forwardly disposed oblique cutting edge 24 formed by grinding off obliquely the periphery 23 as at 25 and grinding an annular recess 26 within said cutting edge 24 to afford clearance for the removed flesh.

The body of the knife 15 for the purpose

hereinafter described has radially-extending slots 27 preferably three in number, a greater number could be employed, and preferably extending from a point adjacent the hub 14 to the periphery of the knife. Each sector enclosed between the slots 27 and an approximately radial line dividing the same are transverse holes 28. These holes 28 are adapted to receive the fingers of a wrench, or any other type of tool, for deflecting said sectors laterally inward or outward toward the axis of the knife to thereby contact the circumference thereof to facilitate the removal of the ring element 23.

15 I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

25 1. A fleshing knife of the class described comprising a disk body radially slotted to permit of the contraction of the disk, and an annular cutter element extending about said body at the periphery.

30 2. A fleshing knife of the class described comprising a conical disk-like body having a groove at its periphery, and an annular cutter element detachably held in said groove.

35 3. A fleshing knife of the class described including a sectored substantially conical metal body adapted to be contracted, and a separate cutter element thereon at the periphery.

40 4. A fleshing knife of the class described including a sectored cast metal body having

a groove at its periphery and adapted to be contracted, and a separate cutter element thereon in said groove, said cutter element presenting an annular cutter edge disposed 45 toward the front of the knife.

5. A fleshing knife of the class described including a sectored body adapted to be contracted, and a separate annular cutter element at the periphery, said body having 50 an annular depression in which said cutter element is detachably seated.

6. A fleshing knife of the class described including a sectored body adapted to be contracted, and a separate annular cutter element at the periphery, said body having an annular depression in which said cutter element is detachably seated, the material of the body extending radially at the back of said groove beyond the material at the front 60 of the groove.

7. In a fleshing knife, a disk grooved at the periphery, and a cutter element formed of wire extending about the disk in said groove.

8. A fleshing knife comprising a revolving element, and a cutter element at the periphery formed of wire, said wire having a cutter edge at the side thereof.

9. A fleshing knife comprising a disk a 70 cutter element at the periphery of said disk formed of piano wire with an annular cutter edge thereon.

10. A fleshing knife comprising a disk having a peripheral groove, and a wire 75 sprung into said groove.

11. A fleshing knife comprising a disk having a groove, a wire cutter element having flat sides at angles to each other arranged in said groove, and a cutter member at the 80 intersection of said sides.

SAMUEL FRIEDMAN.
